Inventor:

Wm H. Hamilton

UNITED STATES PATENT OFFICE.

WILLIAM H. HAMILTON, OF WATROUSVILLE, MICHIGAN.

STUMP-MACHINE.

SPECIFICATION forming part of Letters Patent No. 272,957, dated February 27, 1883.

Application filed May 24, 1882. (No model.)

To all whom it may concern:

Be it known that I, WILLIAM H. HAMILTON, a citizen of the United States, residing at Watrousville, in the county of Tuscola and State of Michigan, have invented certain new and useful Improvements in Stump-Pullers; and I do hereby declare that the following is a full, clear, and exact description of the same, reference being had to the accompanying drawings and the letters of reference marked thereon, which form a part of this specification, and in which—

Figure 1 is a perspective view of my improved stump-puller, and Fig. 2 is a perspective view of the lever detached.

The same letters refer to the same parts in both figures.

This invention relates to machines for extracting stumps; and it consists in certain improvements in the construction of the same, which will be hereinafter more fully described, and particularly pointed out in the claims.

In the drawings hereto annexed, A represents the body of my improved machine, which consists of two horizontal parallel planks, A² A², which are spaced and connected by bolts or braces a a. The said planks are provided near their edges with two series of vertical perforations, b b, so located that the perforations at one side shall register with or be located opposite the spaces between the perforations at the other side, as clearly shown in Fig. 1 of the drawings. D D are pins or bolts fitted in the said perforations, as shown.

O is a plate secured between the planks A² A², at one end of the machine, by means of a bolt and nut, (denoted by e.) Said plate has at its outer end an opening or perforation, d, to receive means for connecting it with a suitable anchoring device, by which the machine may be made fast and held securely in position during operation.

The operating-lever B, which is shown detached in Fig. 2 of the drawings, is provided in its outer side or edge with two recesses, r r, adapted to receive the pins or bolts D D when

the said lever is placed in position between the planks A² A² of the machine.

S is a bail or staple secured to the side of the lever between the recesses r r. The outer end of the lever is provided with a spindle, G, upon which is journaled a wheel, F. H is a chain connected or secured to the staple S of the lever.

In operation, the chain H is connected or made fast to the stump to be extracted. The lever is then moved back in the machine as far as possible, and the pins or bolts D D adjusted in their respective holes, the lever having been so placed that one of the bolts D shall fit in one of the recesses r. Draft is then applied to the outer end of the lever, which, being supported upon the wheel F, will move easily and without dragging. The pins or bolts D are alternately shifted or moved back as the lever in loosening the stump moves back in the frame.

My improved stump-puller is exceedingly simple in construction, durable, and it may be manufactured at a trifling cost.

I claim as my invention and desire to secure by Letters Patent of the United States—

1. In a stump-puller, the combination of the frame or body consisting of two horizontal parallel planks, spaced and connected by bolts or braces, and provided at the edges with vertical perforations, those at one side being located opposite the spaces between those at the other side, the anchoring block or plate C, the pins or bolts D D, and the lever B, having recesses r r and staple S, substantially as and for the purpose set forth.

2. In a stump-puller, the combination, with the frame A, having perforations b b, the anchoring-plate C, and pins or bolts D, of the lever B, having recesses r r, staple S, chain H, spindle G, and wheel F, substantially as and for the purpose set forth.

WILLIAM H. HAMILTON.
